(57) **CLAIM**

The ornamental design for a fluid handling tube, as shown and described.

DESCRIPTION

FIG. 1 is a front perspective view of a fluid handling tube embodiment with attached cap;

FIG. 2 is a back perspective view thereof;

FIG. 3 is a front view thereof;

FIG. 4 is a back view thereof;

FIG. 5 is a side view thereof;

FIG. 6 is a side view thereof;

FIG. 7 is an enlarged top view thereof;

FIG. 8 is an enlarged bottom view thereof;

FIG. 9 is a front perspective view of a fluid handling tube embodiment;

FIG. 10 is a back perspective view thereof;

FIG. 11 is a front view thereof;

FIG. 12 is a back view thereof;

FIG. 13 is a side view thereof;

FIG. 14 is a side view thereof;

FIG. 15 is an enlarged top view thereof; and,

FIG. 16 is an enlarged bottom view thereof.
